TURNSTILE

Edward J. Kennedy, Hollis, N. Y., and John F. Perey, Westwood, N. J., assignors to Perey Manufacturing Company, a corporation of New York

Application August 5, 1931. Serial No. 555,202

16 Claims. (Cl. 194—55)

Our invention relates to coin mechanism suitable for use in turnstiles, weighing, vending and other machines in which the insertion of a coin or a token of predetermined size and/or value is required to effect operation of the machine.

Differing from many mechanisms now in common use, in which the inserted coin serves to close an electric circuit, the present invention is designed to utilize the coin as a mechanical element, in bridging the space between two otherwise separated and disconnected members, to enable motion to be transmitted from one such member to the other, through the interposed coin or token.

In machines, such as turnstiles, which are heavily built for long life and to withstand rough usage, the action is rapid and the parts move with such force as to require specially designed coin mechanism which is structurally strong and comparatively simple, otherwise breakdowns will be of frequent occurrence. As a protection against mutilation of coins used as a mechanical element and consequent jamming of the mechanism, we cause the coins to be engaged edgewise instead of flatwise and thereby avoid troubles of this sort which are more or less common in coin mechanisms now in use.

Another feature of the invention consists in designing the mechanism so that it will respond to coins and tokens which differ in size. This is necessary where some fares are paid in cash while others are paid in metal transfer tokens.

Arranged in cooperative relation to be automatically operated by the coin and token mechanism, we provide two registers, one for cash fares and the other for transfer fares. The selection for operation of the proper register is also automatically effected by the mechanism in responding to the inserted coin or token.

The above mentioned and other important features of the invention will be set forth in detail in the description of the mechanism illustrated in the accompanying drawings, which follows:

For convenience of illustration, we have shown the coin mechanism arranged to control the operation of a turnstile but do not wish to be understood as intending to limit ourselves to this particular combination or to the form or details of the mechanism, as various changes may be made therein within the scope and meaning of the appended claims.

In the drawings:

Fig. 1 is a top plan view of a present day turnstile, showing our invention in use, the top cover

plate of the turnstile being removed to show the contained mechanism.

Fig. 2 is a cross section on the line *a*—*a*, of Fig. 1, showing the coin and token mechanism and the position assumed by an inserted coin of predetermined value, representing a cash fare, before the mechanism begins to operate.

Fig. 3 is a similar view showing the same mechanism after it begins to operate in response to an inserted transfer token, which, it will be noted, is of somewhat larger diameter than the cash fare coin, shown in Fig. 2.

Fig. 4 is a vertical section on the line *d*—*d*, of Fig. 2;

Fig. 5 is a like view on the line *e*—*e*, of Fig. 3; 70
Fig. 6 is a view in cross section on the line *a*—*a*, of Fig. 1.

Fig. 7 is a cross section on the line *b*—*b*, of Fig. 1, and

Fig. 8 is a similar view on the line *c*—*c*, of 75
Fig. 1.

Referring now to the drawings, 1 represents the turnstile shaft, 2, 2, etc., are the usual four equi-spaced turnstile arms, mounted to turn as a unit with the shaft. Fast on the shaft 1, there is a disk 3, having four equi-spaced radially disposed lugs 4, 4, etc., and ratchet teeth 5, between the lugs. Cooperating with the lugs 4, there is a locking pawl 6, held in engaging relation by a spring 7. Normally, or when the turnstile is not in operation, the engaging face of the locking pawl 6, and the adjacent lug 4 of the disk 3, are held somewhat separated, as shown to permit free limited forward motion of the turnstile, regardless of whether the required coin or token is inserted or not. This free limited motion of the turnstile is utilized to advance a coin finder 8, hereinafter more fully described. If the required coin or token has been inserted, the coin finder, on this preliminary advance, will engage the same and through the coin or token, impart the necessary motion to cooperating parts or members to actuate the release lever 9, of the locking pawl 6, and permit the turnstile to complete the operation. If, on the other hand, the coin finder 100 fails to find a coin or token, no motion will be imparted to the release lever and locking pawl will continue to hold the turnstile against further forward rotation.

Loosely mounted on the stud shaft of the locking pawl and spring held in engagement with the ratchet teeth 5 of the disk 3, there is a pawl 10, which holds the turnstile against reverse movement and limits it to forward rotation only.

Cooperating with the lugs 4, 4, etc., of the disk 110

3, a stop pawl 11, is provided which is designed to receive the impact and bring the turnstile to a dead stop at the end of each operation or quarter revolution. This pawl, pivoted at 12, is 5 spring-held normally, with its stop end 11a, clear of the disk lugs, as shown in Fig. 1, and its opposite end or tail 11b, in the path of travel of the lugs.

As the turnstile starts into operation, the nearest disk lug, such as 4a, passes under and clear 10 of the stop pawl 11, until it reaches the tail 11b and engaging its inclined face, trips it, against the action of the pawl spring, throwing and holding the stop end 11a, down into position to engage 15 the next disk lug, such as 4b, as the turnstile completes its operation or quarter revolution. At the instant the stop pawl engages the lug 4b, the lug 4a clears the tail of the pawl, permitting the spring to act and return the stop 20 pawl to its normal position, as shown in Fig. 1, ready for the next operation.

Acting to retard rotation of the turnstile during the first half of its operation, then to accelerate it during the last half and finally to yieldingly maintain the turnstile with one of its arms 25 2, directly across, barring entrance to the passage the turnstile is placed to control, there is a positioning lever 13, pivoted at 14, and held by a strong spring 15, in engagement with spaced 30 rollers 16, 16, etc., on the disk 3. There are four of these rollers 16, equispaced on the disk and the positioning lever engages them in pairs as shown, and so yieldingly holds the turnstile against free movement.

35 The positioning lever 13, has an extension 13a, beyond its pivot, as shown in Fig. 1, and to this extension 13a, a second extension 13b is spring held and secured, in effect, by a hinge joint 17, permitting limited separation of the 40 extensions at their free ends.

The second extension 13b, of the positioning lever 13, is yieldingly held in engagement with the coin finder 8, previously referred to, by a connecting spring 8a. The arrangement is such, that 45 if the coin jams and stops further advance of the coin finder and the extension 13b, the positioning lever 13, including the extension 13a, may make its full movement without breaking or otherwise damaging the mechanism.

50 As shown in Figs. 2 and 3, the coin finder 8, is formed as a slide bar, horizontally disposed and movable in suitable guides 18, extending transversely across, near the bottom of the coin chute 19. Normally, or when the mechanism is not in 55 operation, that portion of the coin finder extending across the coin chute, is flush with and forms, in effect, a continuation of the rear wall 19a thereof, so that when a coin or token is inserted in the chute, through the entrance slot 20, it drops down and comes to rest or lodges between a lug or stud 8b, of the coin finder and the reduced end 9a of the release lever 9. The reduced end 9a of this lever projects through a slot 8c of the coin finder, as shown in Fig. 2.

60 In order to enable the coin chute to be readily cleared of coins, tokens or the like that jam or stick therein and to provide free passage through the same for coins or disks of smaller diameter than the coins and tokens for which the mechanism is designed, the front wall 19b of the chute is hinged, as indicated at 19c, (see Fig. 3), and yieldingly held in position by a spring 19d. By means of a terminal lug 19e, providing a finger hold, the front wall of the chute may be swung 65 outward to facilitate clearing the interior pas-

sage. At the lower end, the chute terminates in a cup 8d, in which the rejected and dislodged coins, disks and the like are caught and held.

It will now be seen that as the positioning lever is given motion, in the operation of the turnstile and advances the coin finder, the latter, engaging the coin or token, edge on, will force it horizontally along and the coin, having an edge on engagement with the projecting end 9a of the release lever 9, will transmit its motion to that lever. The motion thus imparted to the release lever, swings it about its pivot, causing its opposite curved end 9b, engaging a stud 6a of the locking pawl 6, to trip the pawl and free the turnstile for operation.

The next step is to release the coin or token, so the mechanism may return to its normal position, ready for the next operation of the turnstile. This is accomplished by providing the extension 13a of the positioning lever 13, with a stud 21, designed to engage the release lever at a point intermediate its reduced end 9a and its pivot and so advance the release lever at a greater speed than it is being advanced by the coin finder through the coin. This accelerated movement 100 of the release lever carries it clear of the coin and frees the latter for deposit in a suitable receptacle, not shown. The stud 21 is of such length or so proportioned that its engagement with the release lever is timed to occur at the 105 moment the coin, advanced by the coin finder, arrives directly above a vertical chute 22, through which the coin drops into the receptacle above mentioned. The release and deposit of the coin occurs shortly before the turnstile completes its 110 operation and as the positioning lever 13, under the action of its spring 15 and rollers 16, 16, etc., reverses its movements, the stud 21 will be carried clear of the releasing lever 9, permitting it, under the action of its spring 22, to swing back 115 and allow the spring retracted locking pawl to resume its normal position, checking further operation of the turnstile until another coin or token, has been inserted.

Cooperatively associated with the coin mech- 120 anism above described, we have shown two registers, one, indicated at 23, for cash fares, and the other, indicated at 24, for transfers, in the form of metal tokens of somewhat larger diameter than the coins used for cash fares.

The registers are of a form well known in the art and are operated in a well known manner by pawl and ratchet mechanism, as shown in Figs. 7 and 8.

Projecting through slots 30, 31, in the end 130 frame of the mounting of the registers, are two pins 30a, 31a, (see Fig. 6), movement of which from left to right in the slots serves to operate the registers through the ratchet mechanism above referred to.

These pins 30a, 31a, are given movement by means of an arm 32, which is pivoted at 33, to a lug 34 depending from the the free end of the first extension 13a of the positioning lever 13. The free end of the arm has two shouldered recesses, 35, 36, formed in it, one of which (35), opening upward, is spring held normally engaged by the pin 30a of the ratchet mechanism of the cash fare register. The other recess 36, opening downward, is designed to be engaged as the arm 32, is depressed, in a manner to be explained, by the pin 31a, of the ratchet mechanism of the transfer register.

It will be noted that the pins lie at the right hand end of the recesses, as viewed in Fig. 6, and 150

further that these recesses are of such length that there is considerable lost motion before the shoulder at the left hand end of the recess engages the pin. This lost motion is provided to permit the preliminary advance of the coin finder, as above described, without affecting the registers and so limit actuation of the registers to complete operations of the turnstile.

Referring again to Fig. 6, it will be seen that as the positioning arm 13, is given motion by the operation of the turnstile, in response to a coin or cash fare, the arm 32 will be moved to the right until the shoulder at the left hand end of the recess 35 engages the cash fare register pin 30^a. In thus being moved to the right to engage the cash fare register pin 30^a, the arm 32, will clear the transfer register pin 31^a, as will be seen from Fig. 6.

In order to operate the transfer fare register when a transfer token is entered by way of the chute, it is necessary to swing the register operating arm 32 downward, about its pivot, as shown in Fig. 3, so that when advanced its shouldered recess 35 will clear the cash fare register pin 30^a and its shouldered recess 36, will be positioned to engage the transfer fare register pin 31^a. To shift the arm 32, as just described, I utilize the transfer token disk which, as previously stated, is of somewhat larger diameter than the cash fare coin and as it is advanced by the finder 8, to transmit motion to the release lever 9, as above described, it engages the inclined surface 37^a of a lever 37, and swings the same about its pivot 37^b. As a result of this motion, the longer end 37^c of the lever 37, engages a stud 32^a, of the register operating arm 32, and depresses the lever to the above described position, shown in Fig. 6, which causes the left-hand shoulder of the recess 36 to engage the pin 31^a, and operate the transfer fare register.

From the foregoing, it will be seen that the arm 32, is thus made automatically selective in operating the registers and is controlled in its selectivity by the character of the fare paid.

As the operation, advantages, etc., of the mechanism will be apparent from the foregoing, further description thereof will not be given.

Having thus described our invention, what we claim is:

1. A coin-controlled mechanism comprising an approximately L-shaped coin chute provided with entrance and exit openings and having the rectangular cross sectional form throughout of a predetermined coin, a coin finder arranged to enter the chute to engage an inserted coin edge on and move it edge on from the longer leg of the chute to an exit opening in the shorter leg thereof, a member to which motion is transmitted by the coin finder through the aforesaid coin, and means for giving the coin finder and member different speeds at a suitable point in their travel to release the coin.

2. A coin-controlled mechanism comprising an approximately L-shaped coin chute provided with entrance and exit openings and having the rectangular cross sectional form throughout of a predetermined coin, a coin finder arranged to enter the chute to engage an inserted coin edge on and move it edge on from the longer leg of the chute to an exit opening in the shorter leg thereof, a member movable in the shorter leg of the chute and positioned therein to engage an inserted coin edge on, the said member having motion transmitted to it by the coin finder through the aforesaid coin, and means for giving

the coin finder and member different speeds at a suitable point in their travel to release the coin.

3. A coin-controlled mechanism comprising an approximately L-shaped coin chute provided with entrance and exit openings and having the rectangular cross sectional form throughout of a predetermined coin, a coin finder arranged to enter the chute to engage an inserted coin edge on and move it edge on from the longer leg of the chute to an exit opening in the shorter leg thereof, a member to which motion is transmitted by the coin finder through the aforesaid coin, and means for accelerating the movement of the member at a suitable point in its travel to release the coin.

4. A coin-controlled mechanism comprising an approximately L-shaped coin chute provided with entrance and exit openings and having the rectangular cross sectional form throughout of a predetermined coin, a coin finder arranged to enter the chute to engage an inserted coin edge on and move it edge on from the longer leg of the chute to an exit opening in the shorter leg thereof, a member to which motion is transmitted by the coin finder through the aforesaid coin, the coin finder and member combining to form opposite sides of a pocket in which the coin lodges in edge on relation between them, and means for giving the coin finder and member different speeds at a predetermined point in their travel to release the coin.

5. A coin-controlled mechanism comprising an approximately L-shaped coin chute provided with entrance and exit openings and having the rectangular cross sectional form throughout of a predetermined coin, a coin finder arranged to enter the chute to engage an inserted coin edge on and move it edge on from the longer leg of the chute to an exit opening in the shorter leg thereof, a member to which motion is transmitted by the coin finder through the aforesaid coin, the coin finder and member combining to form opposite sides of a pocket in which the coin lodges in edge on relation between them, the said pocket having an opening at the bottom for unobstructed passage of coins of less than a predetermined diameter, and means for giving the coin finder and member different speeds at a suitable point in their travel to release the coin.

6. A coin-controlled mechanism comprising a coin chute provided with an entrance slot, a co-operating coin finder in the form of a slide movable through the chute to engage an inserted coin edge on, a spring for advancing the slide, an actuating member for the slide controlling the spring of the slide, a member normally positioned to be engaged edge on by a coin entered by way of the chute and to which member motion is transmitted by the coin finder through the interposed coin, and an automatic release for the coin.

7. A coin-controlled mechanism comprising a coin chute provided with an entrance slot, a co-operating coin finder in the form of a slide movable through the chute to engage an inserted coin edge on, a spring for advancing the slide, an actuating member for the slide controlling the spring of the slide, a member normally positioned to be engaged edge on by a coin entered by way of the chute and to which member motion is transmitted by the coin finder through the interposed coin, and means for imparting the same speed of travel to the coin finder and the member throughout a portion of their movement and different speeds thereafter to separate the finder and member to release the coin.

8. A coin-controlled mechanism comprising a coin chute provided with an entrance slot, a yielding side wall and an external delivery outlet for rejected coins, a cooperative coin finder in the form of a slide movable through the chute to engage an inserted coin edge on, a spring for advancing the slide, an actuating member for the slide controlling the spring of the slide, a member normally positioned to be engaged edge on by a coin entered by way of the chute and to which member motion is transmitted by the coin finder through the interposed coin, and an automatic release for the coin. 80
9. A coin controlled mechanism comprising a coin chute provided with an entrance slot, a co-operating coin finder in the form of a slide, a spring for advancing the slide, an actuating member for the slide controlling the spring of the slide, a member to which motion is transmitted by the finder through an interposed coin entered by way of the chute, an automatic release for such coins, and an operatively connected register for automatically indicating the number of operations of the mechanism. 85
10. The combination, in a coin and token controlled mechanism, of a coin and token chute provided with an entrance slot, a cooperating coin and token finder, a member to which motion is transmitted by the finder through an interposed coin or token entered by way of the chute, an automatic release for such coins and tokens, operatively connected registers, one for indicating the number of operations of the coin mechanism in response to coins inserted and the other for like indication of similar operations in response to coin-like tokens inserted of a size differing from the coins and a selector for actuating the proper register, the said selector being normally positioned to actuate one of the registers. 90
11. The combination, in a coin and token controlled mechanism of a coin and token chute provided with an entrance slot, a cooperating coin and token finder, a member to which motion is transmitted by the finder through an interposed coin or token entered by way of the chute, an automatic release for such coins and tokens, operatively connected registers, one for indicating the number of coins entered and the other for indicating the number of tokens entered, and an automatic selector for actuating the proper register the said selector being normally positioned to actuate one of the registers. 95
12. The combination, in a coin and token controlled mechanism of a coin and token chute provided with an entrance slot, a cooperating coin and token finder, a member to which motion is transmitted by the finder through an interposed coin or token entered by way of the chute, an automatic release for such coins and tokens, operatively connected registers, one for indicating the number of coins entered and the other for indicating the number of tokens entered, and means for utilizing the inserted coins and tokens to select the register to be operated the said means being normally positioned for operating one of the registers. 100
13. The combination, in a coin and token controlled mechanism of a coin and token chute provided with an entrance slot, a cooperating coin and token finder, a member to which motion is transmitted by the finder through an interposed coin or token entered by way of the chute, an automatic release for such coin and token, operatively connected registers, one for indicating the number of coins entered and the other for indicating the number of tokens entered, and a register operating device common to both registers and controlled in its selection of the register to be operated by the size of the coins and tokens inserted the said device being normally positioned to actuate one of the registers. 105
14. The combination, in a coin and token controlled mechanism of a coin and token chute provided with an entrance slot, a cooperating coin and token finder, a member to which motion is transmitted by the finder through an interposed coin or token entered by way of the chute, an automatic release for such coins and tokens, operatively connected registers, one for indicating the number of coins entered and the other for indicating the number of tokens entered, an automatic selector for actuating the proper register, the said selector being normally positioned to actuate one of the registers and a common source of motion for operating the coin and token finder and the automatic selector. 110
15. The combination, in a coin and token controlled mechanism, of a coin and token chute provided with an entrance slot, a cooperating coin and token finder, a member to which motion is transmitted by the finder through an interposed coin or token entered by way of the chute, an automatic release for such coins and tokens, operatively connected registers, one for indicating the number of coins entered and the other for indicating the number of tokens entered, an automatic selector normally positioned to actuate one of the registers and shiftable to a different position for actuating the other register, means for utilizing one of the two aforesaid types of inserted fare disks to shift the selector, and a common source of motion for operating the coin and token finder and the automatic selector. 115
16. The combination, in a coin and token controlled mechanism, of a coin and token chute provided with an entrance slot, a cooperating coin and token finder, a member to which motion is transmitted by the finder through an interposed coin or token entered by way of the chute, an automatic release for such coins and tokens, operatively connected registers, one for indicating the number of coins entered and the other for indicating the number of tokens entered, an automatic selector normally positioned for actuating one of the registers and shiftable to a different position for actuating the other register, means for utilizing the inserted tokens to shift the selector, and a common source of motion for operating the coin and token finder and the automatic selector. 120
